United States Patent Office

Des. 202,688
Patented Nov. 2, 1965

202,688

SODA DRAFT ARM, OR SIMILAR ARTICLE

Richard T. Cornelius, Minneapolis, and James R. Reischow, Edina, Minn., assignors to The Cornelius Company, Anoka, Minn., a corporation of Minnesota

Filed Oct. 28, 1964, Ser. No. 82,354

Term of patent 14 years

(Cl. D2—3)

FIG. 1 is a front perspective view of a soda draft arm showing our new design.

FIG. 2 is a rear perspective view thereof.

FIG. 3 is a front elevational view thereof.

FIG. 4 is a side elevational view thereof, the opposite side having an appearance which is a reversal thereof.

FIG. 5 is a top plan view thereof.

We claim:

The ornamental design for a soda draft arm, or similar article, substantially as shown and described.
